COMPENSATING ASTRAGAL

John F. Powell, St. Louis County, Mo., assignor
to Vennegut Hardware Company, Indianapolis,
Ind., a Corporation of Indiana

Application October 16, 1931. Serial No. 569,153

1 Claim. (Cl. 20—35)

This invention relates generally to doors and more particularly to a compensating astragal therefor.

In doors, particularly such as are used in theatres, churches, schools, and other places where large gatherings of persons occur, it is desirable that the doors swing freely without, however, having large space between the stiles of the doors when the latter are closed. Such doors are generally equipped with fire and panic exit devices and open automatically when pressure is applied thereagainst. However, if such doors are fitted closely, they are liable to bind and stick when the wood expands, thereby defeating the purposes of such automatic exit devices. On the other hand, if allowance is made for expansion, comparatively large space is left between the two door sections and cold air is thus permitted to enter the building and the appearance of the door is impaired by the unsightly large spaces.

It is the object of the present invention to provide a door having a compensating astragal which can be adjusted relatively to said door so as to maintain at all times the necessary operating clearance between the meeting edges of the door sections, the variations in the widths of the doors produced by expansion or shrinkage of wood being compensated for by the adjustment of said astragal.

Other objects of the invention are to provide a device by means of which the astragal can be supported on the stile of a door at a plurality of spaced points, said devices being adjustable to move said astragal relatively to said stile, thereby maintaining the required operating clearance between said astragal and the adjacent member and eliminating all danger of binding of the door.

Additional objects of the invention are to provide a compensating astragal which is adjustably supported by and engageable with a stile of a door and which can be adjusted to compensate for the variations in widths produced in the door by the shrinkage and/or expansion of wood from which the door is made.

With these and other objects in view, my invention consists in certain novel features of construction and arrangement of parts, hereinafter more fully described and claimed, and illustrated in the accompanying drawing, in which—

Figure 1 is a large horizontal cross section taken through the stiles of two cooperating doors.

Figure 2 is an edge elevational view of a door equipped with my compensating astragal.

Figure 3 is a vertical cross section taken on line 3—3 of Figure 1.

Referring by numerals to the accompanying drawing, 10 and 11 indicate doors which are arranged in cooperative relation and which are mounted to swing in the directions indicated by arrows in Figure 1. Door 10 is provided with a stile 12 which has fixed to its outer edge an astragal 14. Door 11 has a stile 15 on the outer edge of which is mounted a compensating astragal 16.

The opposed faces A of the astragals consist each of a portion B which are disposed parallel to each other and a portion C which are disposed obliquely to the plane of the respective portion B. Portions B of the astragals can be arranged in close proximity to each other so as to reduce the space therebetween to minimum and portions C provide the necessary operating clearance to permit swinging movements of the door.

Both astragals are substantially alike in external appearance and in cross sectional contours. They are both substantially channel-shape in cross section, having parallel portions 14^a and 16^a, respectively, which overlap the edges of the corresponding stiles.

Astragal 14 is made fast to stile 12 but astragal 16 is adjustably mounted on stile 15 by means of compensating devices 17. These latter are arranged in spaced relation throughout the height of said astragal, as shown in Figure 2, where four of said compensating devices are illustrated.

Each compensating device consists of a plate 18 fixed to stile 15 and having a threaded opening 19 and a screw 20 fixed to astragal 16 and engaging said opening 19 of plate 18.

The edge of the stile 15 is provided with recesses or pockets 21 of sufficient depths and each plate 18 is arranged in the bottom of each pocket and is secured in position by screws 22. Extending inwardly from each pocket coaxial with opening 19 of the respective plate 18 is a bore 24 which is of larger diameter than that of opening 19 and receives the end of screw 22.

The head 20^a of said screw is arranged in a cup-shaped member 25 which is countersunk in the face A of astragal 16. Thus the annular edges of cup members 25, as well as the heads 20^a, are disposed below the plane of said face and do not interfere with the operation thereof.

Cup member 25 is provided in its bottom with an opening 26 and that portion of the astragal between the bottom of member 25 and the inner face D of the astragal is provided with a bore 27 which is arranged coaxially with said opening 26. Both of these openings are preferably larger than the diameter of screw 22 and the latter

extends therethrough into engagement with plate 18.

Bearing against face D is a washer 28 having an opening of sufficient diameter to clear screw 20. A nut 29 is screw-threaded on said screw and bears against washer 28. This nut is locked against accidental rotation by a lock washer 30 and a lock nut 31. Lock washer 30 is placed between said nuts and when lock nut 31 is drawn tight said nuts 29 and 31 are held against rotation with respect to screw 20. Thus said screw is locked against longitudinal movement with respect to astragal 16 but is permitted rotative movement relatively thereto. When the screw 20 is rotated by the engagement of head 20^a, said screw is moved longitudinally relatively to the stile by virtue of its engagement with plate 18, thereby adjusting the astragal 16 toward or from the stile 15, depending on the direction of rotation of nuts 20^a. In this manner, astragal 16 can be adjusted so as to maintain proper relation with the fast astragal 14 without the necessity of rehanging the door. The variations in width produced in the door by the shrinkage of wood can be readily compensated for by the adjustment of said astragal 16.

The compensating astragal is of the same appearance as the fast astragal and consequently does not detract from the general appearance of the door. The adjusting devices 17 are not conspicuous and are not visible when the door is closed.

As the compensating astragal can be easily adjusted the desired clearance between the astragals of the doors can be maintained at all times.

While I have shown and described herein the preferred form of my invention, it is obvious that various changes in the construction and arrangement of parts of my compensating astragal can be made and substituted for those herein disclosed without departing from the spirit of my invention.

I claim:

In a door construction, the combination with a wooden stile having a plurality of spaced inwardly extending pockets formed in its outer edge, of an astragal matable with the said outer edge and perforated with a series of perforations registrable with the stile pockets, a corresponding plurality of metal cups embedded in the outer ends of the astragal perforations, a corresponding plurality of screws journaled in the astragal perforations and axially fixed relative to the astragal, a corresponding plurality of threaded elements one mounted in each of the stile pockets and adapted to mate with the threaded inner ends of the screws, each of said screws having a non-circular outer end of less diameter than the internal diameter of the adjacent cup and an axial extent no greater than the cup depth.
